(57) **CLAIM**

The ornamental design for a mobile phone, as shown and described.

DESCRIPTION

FIG. 1 is a perspective view of a mobile phone showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the figures that define regions within the claim, and are immediately adjacent to the claimed surfaces, represent the bounds of the claimed design. The broken line showings of icons and a sensor on the front face are directed to environment and are for illustrative purposes only. The broken lines form no part of the claimed design.

1 Claim, 6 Drawing Sheets
